UNITED STATES PATENT OFFICE.

HENRY SOMMER, JR., OF NEWARK, NEW JERSEY.

DESIGN FOR A MATCH-BOX.

Specification forming part of Design No. 5,856, dated May 14, 1872.

To all whom it may concern:

Be it known that I, HENRY SOMMER, Jr., of Newark, in the county of Essex and State of New Jersey, have invented a new and useful Design for Match-Safe, of which the following is a specification:

My design is fully represented in the accompanying photographic illustration, to which reference is made.

B is the lid, which is made to open and shut. C is the box for the reception of the matches.

d is an opening or recess to afford facility for removing a match without first having to raise the lid. e is a ring by which to hang the box. A is a blank space, which may be used for advertising.

What I claim as my invention is—
The design for a match-box, as shown.

HENRY SOMMER, JR.
